UNITED STATES PATENT OFFICE.

HENRY J. DAVIS, OF NILES, OHIO.

ROLLING-MILL GUIDE.

1,017,283.

Specification of Letters Patent.

Patented Feb. 13, 1912.

Application filed April 18, 1911. Serial No. 621,931.

To all whom it may concern:

Be it known that I, HENRY J. DAVIS, a citizen of the United States, residing at Niles, in the county of Trumbull and State of Ohio, have invented certain new and useful Improvements in Rolling-Mill Guides, of which the following is a specification.

This invention relates to the subject of metal rolling, and particularly to an improved delivery guide for the material to be rolled.

The object of the invention is to provide a simple and practical construction of rolling mill guide embodying means that insure the correct alining of the metal bar with the passes of the rolls, and also to prevent the spreading or opening of the end of the bar to an extent that would interfere with the entrance thereof between the rolls. In this connection, it is well understood by those familiar with the art that a difficulty commonly experienced in rolling mill operations, and even with the use of some types of rolling mill guides, is that the heated bar opens or spreads at the end the instant it is released from the pressure of the rolls, and for that reason it is impossible to roll iron on what is usually known as a "continuous mill," wherein a series of sets of rolls are set up in alinement, each succeeding set providing for a further reduction of the bar. When the bar opens or spreads on the end upon leaving the rolls, the same is liable to yield to its tendency to straddle one of the rolls on the next set rather than to enter the passes of such rolls, and for that reason it is usually necessary to pass the bar back and forth through different passes in the same set of rolls. This, of course, is not the case with steel, which does not open or spread at the end in the same manner as an iron bar when being rolled.

Therefore, one of the distinctive objects of the present invention is to provide a guide the several elements of which are so arranged, and capable of such adjustment that the guides proper may be held close to the bite of the rolls, thus preventing the opening or spreading of the front end of the bar, as it emerges from the rolls. Also, the improved guide is of such a construction as to admit of a close adjustment for the guide members proper, while at the same time providing all the rigidity that is necessary for unyieldingly holding the guide members backed up in their guiding position.

With these and other objects in view,

which will more readily appear as the nature of the invention is better understood, the same consists in the novel construction, combination and arrangement of parts hereinafter more fully described, illustrated and claimed.

One of the practical embodiments of the invention is suggested in the accompanying drawings, in which:—

Figure 1 is a front elevation of a rolling mill guide constructed in accordance with the present invention and shown applied to the housings for a set of rolls. Fig. 2 is a vertical sectional view on the line 2—2 of Fig. 1. Fig. 3 is a horizontal sectional view on the line 3—3 of Fig. 2. Fig. 4 is a detail perspective view showing the U-shaped guide holder or retainer and the guide box which is intended to be loosely seated therein, these elements being shown in separated relation.

Like references designate corresponding parts in the several figures of the drawings.

In carrying out the invention, no change or alteration is required in the usual parts of a rolling mill, so for illustrative purposes there is shown in the drawings one set or pair of rolls 1—1 mounted in the ordinary manner in the usual roll housings 2 of the conventional construction to provide for the removable mounting of the rolls therein.

According to the present invention, the opposite roll housings 2 are provided upon their inner sides back of the discharging or out-going side of the rolls with longitudinally arranged holding grooves 3 formed in any suitable manner and closed at the upper and lower ends as at 4 and 4^a and also at the outer and inner sides thereof as at 5 and 6 respectively, but a feature of the invention is to provide the inner wall portion 6 of each holding groove 3 with a lateral clearance opening 7 which permits the insertion and removal of the supporting bars 8 in a manner to be presently referred to.

Aside from the holding grooves 3, the rolling mill guide, as an entirety, essentially comprises a pair of the supporting bars 8 held in spaced relation and lying in horizontal parallel planes, and each of said supporting bars constitutes the supporting member for a guide holder or retainer 9. This guide holder or retainer is in yoke form, that is to say, consists of a U-shaped piece or block having the opposite parallel side legs 10 and the outer end piece 11 connecting the outer ends of the side legs, thus

providing an element constructed with what may be termed an open guide seat which loosely and detachably receives therein the guide member proper 12.

5 The guide member 12 consists of a block that registers in the socket or seat of the guide holder 9, and also rests against the supporting bar 8 carrying the latter. Furthermore, the guide block or member 12 10 is provided on its guiding face with a channel or groove 13 that corresponds in cross sectional form to the shape of the roll passes, and serves to receive the front end of the bar immediately as it leaves the rolls, 15 and to fit the same with sufficient closeness to prevent the spreading thereof, which has been previously referred to.

In addition to the features referred to, 20 each guide block or member 12 is beveled on its back, as indicated at 15, to permit the inner nose portion of the said block or member to be adjusted closely into the passes of the rolls, and into very close proximity to the bite of the latter, thus 25 securing the functions and advantages hereinbefore referred to.

It will of course be understood that the 30 guide holders and guide blocks carried by the two supporting bars 8 are arranged, in inverted and superposed relation, as shown in the drawings, so that the two guide blocks form a complete tubular guide through which the metal bar is guided. In connection with the mounting of these 35 parts of the device, it will be noted that the side legs 10 of the guide holders are provided with longitudinally arranged adjustment slots 16 which receive retaining bolts or equivalent fasteners 17 that pass through 40 the bars 8 and provide means whereby the guide members proper may be closely adjusted to the roll passes, while at the same time the guide holders serve to rigidly back up said members in their adjusted position.

45 The supporting bars 8 are provided at their extremities with dowel elements or tongues 18 that are inserted laterally through the clearance openings 7, and carried out of the same, when the bars are 50 respectively placed into and taken out of, their holding groove. And the bars are rigidly held in their spaced apart position and also rigidly wedged in their holding 55 grooves by the simple expedient of chocking struts 19, wedged into the holding grooves respectively above and below the uppermost bar 8 at the ends thereof. If the adjustment of the parts required it, similar struts could also be placed below the 60 lowermost supporting bar 8.

I claim:

1. In a rolling mill guide, the roll hous-

ing, a pair of supporting bars mounted between the housing, a guide holder mounted on each supporting bar, and a guide member 65 loosely and detachably seated in the holder.

2. In a rolling mill guide, the roll housings, a pair of supporting bars mounted between the housings, a guide holder mounted on each supporting bar, and a guide member loosely and detachably seated within the holder and also seated on the supporting bar, the holders and guide members on the opposite bars being arranged in inverted 70 relation.

3. In a rolling mill guide, the roll housings, a pair of supporting bars mounted between the housings, a guide holder mounted on each supporting bar and adjustable 75 transversely of the latter toward and from the rolls, and a separate guide member loosely and detachably seated in each holder.

4. In a rolling mill guide, the roll housings, a pair of supporting bars mounted between the housings, a U-shaped guide holder 80 mounted on each supporting bar and having its open end next to the mill rolls, and a separate guide member loosely seated in the guide holder and projecting through and beyond the open end thereof.

5. In a rolling mill guide, the roll housings, a pair of supporting bars mounted between the housings, a guide holder consisting of a yoke piece mounted on each supporting bar and having an open end next to 95 the mill rolls, and a separate guide member detachably seated in each holder.

6. In a rolling mill guide, the roll housings, a pair of supporting bars mounted between the housings, a U-shaped guide holder 100 adjustably clamped on each bar and having its open end next to the mill rolls, and a separate channeled guide block detachably seated in each holder and having a beveled back.

7. In a rolling mill guide, the roll housings provided upon their inner sides with holding grooves closed at their upper and lower ends and sides, and provided in their inner walls with openings located at an intermediate point, supporting bars having end portions received within the grooves and adapted to be passed through said lateral openings, guide members carried with the supporting bars, and chocking elements 110 adapted to fit the grooves and engage with the supporting bars.

In testimony whereof I hereunto affix my signature in the presence of two witnesses.

HENRY J. DAVIS.
